UNITED STATES PATENT OFFICE.

JOHN ARTHUR WEIS, OF CHICAGO, ILLINOIS.

JET-PROPELLED BOAT.

Application filed July 2, 1927. Serial No. 203,125.

This invention relates to boats which are driven and maneuvered by jet propulsion.

The main objects of this invention are to provide an improved form of boat having jet propulsion which is so arranged that it will be relatively stable in rough waters; to provide a jet propelled boat which will be raised from the water, thereby decreasing its resistance and increasing its speed at the same time that it was propelled forwardly; and to provide a jet propelled boat which can be readily controlled both in a forward and rearward direction, quickly stopped and which can be quickly maneuvered at all times.

15 An illustrative embodiment of this invention is shown in the accompanying drawings in which:

Figure 1 is a side elevation of the boat in its normal position in the water.

20 Fig. 2 is a stern end elevation of the same.

Fig. 3 is a bottom plan view of the same.

Fig. 4 is a side elevation of the same when being propelled forwardly and shows how the boat is raised out of the water at the time 25 of its forward propulsion.

Fig. 5 is a stern end elevation of the same when traveling on rough water showing how the propelling jets of water maintain a substantially even keel of the boat at all times.

30 Heretofore in the construction of jet propelled boats, discharge jets or nozzles have been placed along the sides, bottom and ends of the boats in various positions, but none of such constructions have had either of the two main objects of this invention in mind in their designing. In the present construction, the discharge nozzles or jets are arranged to slant downwardly and rearwardly so as to lift the boat, and particularly the front end thereof, 35 from the water when the boat is being propelled. This lifting of the boat from the water will, of course, decrease resistance, thereby increasing its speed.

The other main feature of the present construction is that the discharge jets are confined to the side marginal edges of the boat closely adjacent the normal water line thereof, none of the jets being located along the bottom of the boat or near its keel. With this arrangement of the jets when the boat is traveling over rough water, the discharged streams of water strike the surface of the body of water and tend to support the boat on an even keel at all times.

55 An illustrative embodiment of this invention is shown in the accompanying drawings

which are more or less diagrammatic, the interior pumping mechanism not being shown or described. A boat 1 is provided along its side marginal edges adjacent the normal water line with a series of downwardly and rearwardly slanting discharge nozzles 2. These nozzles may be in alinement or in somewhat staggered relationship with respect of the normal water line of the boat as shown 60 particularly in Figs. 1 and 4. A majority of the nozzles are preferably placed on the front half of the boat, so as to lift the bow 65 more than the stern.

A series of intake nozzles 3 are provided 70 along the sides of the boat on a plane lower than the discharge nozzles so as to be normally underneath the water at all times. Suitable pumping machinery, not shown, is provided within the boat for drawing the 75 water into intake nozzles 3 and discharging it through the various discharge nozzles.

Located on each side of the bow and inclined downwardly and to the front is a pair 80 of discharge nozzles 5 which provide a brake for the quick stopping of the boat when desired.

The stern of the boat is provided with a flat fan-shaped discharge nozzle 6 which acts as a rudder for guiding the boat. This nozzle rudder 6 is mounted so as to be horizontally swingable for guiding the boat in the usual manner.

In the operation of this boat, the water is drawn in through the intake nozzles 3 by 85 suitable pumping machinery, not shown, and if it is desired to move the boat forwardly, the water is discharged out through all of the discharge nozzles 2. This lifts the front end of the boat from the water and propels it 90 forwardly at the same time. The direction of the boat can be determined by the positioning of the rudder nozzle 6 through which water is discharged either intermittently or continuously.

When it is desired to quickly stop the boat, the water is shut off from the discharge nozzles 2 and turned into the discharge nozzles 5. This acts as a quick stopping brake and at the same time permits the front end of the boat to come down into the water, thus aiding in its stopping.

If it is desired to move the boat bodily side-wise, the water is turned into the discharge nozzles 2 on one side of the boat only and at the same time through the discharge nozzle 5 located on the same side of the boat. The noz-

zle 5 counteracts the action of the nozzles 2 and causes the boat to be moved bodily side-
wise.

Although but one specific embodiment of
5 this invention has been herein shown and de-
scribed, it will be understood that numerous
details of the construction shown may be al-
tered or omitted without departing from the
spirit of this invention as defined by the fol-
10 lowing claims.

I claim:

1. A water jet propelled boat having water

intake means, a plurality of water discharge
nozzles confined to the side marginal edges
adjacent the normal water line of the boat, 15
and pumping means therefor.

2. A jet propelled boat having a series of
downwardly and rearwardly inclined water
discharge nozzles having their location con-
fined to the side marginal edges adjacent the 20
normal water line thereof.

Signed at Chicago this 30th day of June,
1927.

JOHN ARTHUR WEIS.
